UNITED STATES PATENT OFFICE

GEORGE CHARLES LEWIS, OF NEW DORP, NEW YORK, ASSIGNOR TO COLUMBIAN
CARBON COMPANY, OF NEW YORK, N. Y., A CORPORATION OF DELAWARE

MANUFACTURE OF CARBON BLACK

Application filed October 1, 1930. Serial No. 485,582.

This invention relates to the manufacture of carbon black and constitutes an improvement in the apparatus and process shown and broadly claimed in my U. S. Patent 1,510,485, in which the quantities of the carbon black are increased and the quality improved by the passage of an electric current through the flame from which the carbon is deposited.

10 In the production of carbon black it is the usual practice to cause a gas burner to impinge on a depositing surface having a lower temperature than the temperature of the flame, so that carbon black is condensed thereon. In the specific form illustrated in 15 said Patent 1,510,485, the carbon forming flame had a metal rod extending through the flame at a distance from the depositing plate, and at a point just above the point of maximum heat. The depositing plate and rod 20 were connected to a suitable source of electric energy so that the current passed therebetween in the flame. This rod in operation was moved endwise in order to facilitate the 25 removal of the carbon black deposited thereon.

One object of the present invention is to provide a simpler process and arrangement for electrifying the carbon forming flame.

30 Another object is to provide an electrode of the electric current which is less apt to have carbon deposited thereon, and which therefore need not be mechanically moved back and forth through the flame.

35 A further object of the present invention is to provide an electrode at a position whereby the current is emitted from a point so that better discharge of current is effected.

40 In a specific embodiment of the present invention, an electrode in the form of a clip or wire is provided which may advantageously have electrical contact with a pipe line, so that the latter constitutes a main 45 conduit for a plurality of burners extending therefrom. The current-discharging portion of the clip or wire in order to obtain favorable results should reach little if any further than the tip or slot of the burner.

50 In this position the current discharging por-

tion of the clip would be disposed in the blue region of the flame where there is less tendency to form carbon black.

The tip of the burner may be made of any suitable material. However, it has been 55 found advantageous to use a lava tip which is less subjected to radiation and which will retain its heat sufficiently to obviate the condensation of any carbon black thereon.

The invention consists in the new and improved features of construction and the new and improved arrangements and combinations of steps in the process hereinafter described and more particularly set forth in 60 the claims.

Although the novel features which are believed to be characteristic of this invention will be particularly pointed out in the appended claims, the invention itself, as to its objects and advantages, the mode of its operation and the manner of its organization may be better understood by referring to the following description taken in connection with the accompanying drawing forming a part 70 thereof, in which the single figure is a somewhat diagrammatic perspective view of an apparatus constructed in accordance with my invention.

In practice there are provided a plurality 75 of depositing plates or members, although I have illustrated but one in the form of channels 10. The usual means for moving them back and forth endwise and for supporting and guiding them, and for brushing off the deposited black, have not been illustrated, as they may be constructed in accordance with the usual practice or as shown in my prior 85 patent above referred to.

Beneath each channel are a plurality of 90 burners 16 so positioned that the upper portion of the flame emitted from each burner plays on the under surface of the plate forming the bottom of the channel. The burners for each channel may be arranged in a row 95 along a gas pipe 15, which supplies all of the burners. Each of the burners 16 has a tip 17 provided with a slot 18 to effect a fan-shaped flame.

As the important feature of my invention 100 each of said burners 16 has an electrode

which may take the form of a clip or wire 19 having one portion or end thereof secured to a source of electric current. The terminal preferably extends in the same general direction as the direction of the flame from the burner 16. It is advantageous to have the terminal or current discharging end of each clip extend but little further than the slot 18. In this way the electrode or pole will be disposed in the blue region of the flame where there is less tendency for carbon black or soot to collect thereon.

Although the electrodes 19 may be connected to a current supply wire, the pipe line 15 preferably serves as one conductor and the channel as the other. As shown, a source of electrical energy 20 has one terminal thereof connected to the channel 10 so that the latter forms one electrode, and the other terminal connected to the main pipe line 15 and through it to the electrodes 19. Each of the electrodes 19 has an electrical connection with said pipe lines.

It should be understood that the supports 25 for the various members of opposite polarity must be so insulated from each other as to prevent the flow of the current except through the flame, so that all of the current flows through the flame and lengthwise of the latter. Preferably the channel 10 is connected to the positive terminal of the source, and the pipe 15 to the negative terminal.

The tip 17 may be made of any composition. However, it has been found favorable to use a lava tip which will retain its heat sufficiently to obviate the condensation of carbon black thereon. I may make the tip of metal, in which case the tip itself serves 40 as the electrode and the clip or separate electrode may be omitted. One such metal tip 17a is illustrated.

It should be noted that in the present invention any disturbance of the flame by the 45 action of any parts moving therethrough, other than the channel, is obviated. It should also be noted that a better current discharge is effected from the point of the electrode instead of from the side of a wire 50 or rod, and the possibility of a deposition of any carbon black on the electrode is minimized. A lesser number of parts are required, so that the apparatus is cheaper to manufacture. There are fewer moving 55 parts, so that less power is required and there is less liability of getting out of order.

While certain novel features of the invention have been shown and described and are pointed out in the annexed claims, it will be 60 understood that various omissions, substitutions and changes in the forms and details of the device illustrated, and in its operation, may be made by those skilled in the art without departing from the spirit of the invention.

Having thus described my invention, what I claim as new and desire to secure by Letters Patent is:

1. An apparatus for producing carbonaceous deposits from a flame, including means for passing an electric current through the flame, said means including a depositing surface connected to one pole of a source of electrical current, and a wire connected to the opposite pole of said source and having the current-discharging end thereof extending in a direction substantially in the direction of propagation of the flame, said end being disposed near the source of origin of said flame.

2. An apparatus for producing carbonaceous deposits from a flame, including a metal member on which the flame plays and upon which the carbon black is deposited, a gas burner having a tip for producing a flame, means for passing an electric current through the flame, said means including a wire connected to one pole of a source of electric current and having the current discharging end thereof disposed closely adjacent to the tip, and means for connecting said member to the opposite pole of said source.

3. An apparatus for producing carbonaceous deposits from a flame, including a metal member on which the flame plays and upon which the carbon black is deposited, a gas burner having a lava tip at the end thereof for producing a flame, an electrode having the current-discharging end thereof terminating closely adjacent to the tip, and means for connecting said electrode and said metal member to the opposite poles of a source of the electrical energy.

4. An apparatus for making carbon black, including a gas supply pipe having a plurality of burner tips of insulating material, a collecting member for the carbon black and on which the flames play, a source of electrical energy connected to said member and said pipe, and a plurality of electrodes connected to said pipe, and each terminating at the upper end of a separate tip.

5. An apparatus for making carbon black, including a gas supply pipe having a plurality of burner tips, a collecting member for the carbon black, and on which the flames play, and a source of electrical energy connected to said member and said pipe, whereby a separate current passes through each flame between said pipe and said member.

6. An apparatus for making carbon black, including a collecting member, a plurality of burners arranged to produce flames playing thereon, and each having a separate electrode closely adjacent thereto, and means for connecting said electrodes in parallel with each other and in series with said member, whereby current is passed through said flames.

7. An apparatus for producing carbon black, including a collecting plate, a gas supply pipe having a plurality of burners, a

separate electrode closely adjacent to each burner and connected to said pipe, said pipe and said plate being connected to opposite poles of a source of electrical energy.

8. An apparatus for producing free carbon, including a fuel supply pipe having a plurality of burners, a separate electrode closely adjacent to each burner, an electrode above the flames from the burners, and a source of electrical energy having one pole connected to said last mentioned electrode and the other pole to all of said first mentioned electrodes.

Signed at New York, in the county of New York and State of New York, this 29th day of September A. D. 1930.
